Commandr. M. Carpenter of Lancaster Pennsylvania
Setters Patent

The Schedule referred to in these Letters Patent, and making part of the same, containing a description in the words of the word to man, and M. Carpenter himself of his improvement in the plane that makes the tongue or jointing board commonly called the Groove plane. —

To all persons to whom these presents shall come, Emmanuel M. Carpenter, of the City of Lancaster State of Pennsylvania, Plane maker, sends Greeting. Be it known that the said Emmanuel M. Carpenter have invented, constructed, made and applied to his a new and useful improvement in the plane that makes the tongue or jointing of boards commonly called the Groove plane. —

This improvement consists in making his mouths to the plane either square or oblique with a separate bit or iron or wedge for each leaving a small piece of the stalk between the two bits, nearly the size of the tongue intended to be made. And a further improvement on the iron or bits of the groove plane now in use, which consists in having two iron or bits, which when put together, resemble the bit or iron in common use. —

These two bits or irons are then fastened together by a plate or plates on the back thereof. Fig. No. 1. has the one side of the stalk secured to the one side of the bit or iron as near to each end of the plate as a mortise cut orways. A screw is then screwed into the other iron or bit opposite to those mortises so that the iron or bits may be placed close together, or moved farther apart as secured at any necessary distance. Fig. No. 2. has the same bits with Fig. 1. with two plates on the back thereof, one of which is soldered to the top, so as to strengthen the bit at that part. The mortise opposite this plate is cut in one of the bits, or iron. — by a screw through of these plates as moved or fastened as in fig. one. Fig. No. 3. has the same bits as mentioned, with a mortise cut in each of them near the

(540)

top, which are, being comminced, in the upper sides of the bit, wherein
are sliding from each other, as they progress towards the upper
end of the bit. The plate on the back of these bits, have two small
co-screws, which slide in these notches, so near the lower end
of the plate as to be nearly similar to those in the bit, so as
which are also fastened by screws, so as will the bits wherein,
so that by moving the plate upwards, the bits wherein are drawn
together, on drawing the plate downwards, they are separated,
as may be demanded fast at any distance required.

In testimony that the above is a true specification of my
said improvement, as above described, I have hereunto set my
hand and seal the twenty fifth day of Nov. . . . A.D. one thousand
Eight hundred and twenty nine
